UNITED STATES PATENT OFFICE.

HOWARD M. LEONARD, OF JACKSON, MICHIGAN, ASSIGNOR TO RUBY MANUFACTURING COMPANY, OF JACKSON, MICHIGAN.

WALL STRUCTURE.

1,230,181.

Specification of Letters Patent. Patented June 19, 1917.

Application filed February 26, 1912. Serial No. 680,107.

To all whom it may concern:

Be it known that I, HOWARD M. LEONARD, a citizen of the United States, residing at the city of Jackson, county of Jackson, and 5 State of Michigan, have invented certain new and useful Improvements in Wall Structures, of which the following is a specification.

This invention relates to improvements in 10 wall structures.

The wall is especially adapted for use as the side walls of a house or as a sign board.

The objects of the invention are,—

First, to provide improved supports for 15 interchangeable metallic wall sections.

Second, to provide improved attaching means for securing the detachable wall sections in place.

Third, to provide an improved construction 20 of detachable interchangeable wall section.

Fourth, to provide an improved corner structure for walls.

Fifth, to provide an improved wall structure 25 in sections especially well adapted for the insertion of a door, window, or other opening.

Further objects, and objects relating to economies and details of construction and 30 operation will definitely appear from the detailed description to follow.

I accomplish the objects of my invention by the devices and means described in the following specification. The invention is 35 clearly defined and pointed out in the claims.

A structure constituting a preferred embodiment of my invention is fully illustrated in the accompanying drawing, forming 40 a part of this specification, in which:

Figure I is a detail side elevation view of a wall structure embodying the features of my invention, certain portions being broken away to show details.

45 Fig. II is a plan view of the corner structure, the same being taken from the upper left hand portion of Fig. I.

Fig. III is an enlarged detail sectional elevation taken on line 3—3 of Figs. I and 50 II.

Fig. IV is an enlarged detail sectional view on line 4—4 of Fig. II, showing details of the attaching means as incorporated into the corner structure.

Fig. V is a detail perspective view of the corner clip plate 8. 55

Fig. VI is an enlarged detail sectional view on line 6—6 of Fig. I, showing the details of construction and connection to one of the posts and stringers.

Fig. VII is a detail perspective view of 60 one of the connecting clip plates between the posts and stringer in the side wall.

Fig. VIII is an enlarged detail view of the interchangeable wall section structure, portions being broken away to show details. 65

Fig. IX is an enlarged detail view on 70 line 9—9 of Fig. VIII, showing the method of forming the tongue and the manner in which the tongues engage to close the joint between the wall sections.

Fig. X is a detail perspective view of the preferred embodiment of stringer and attaching lug suitably welded thereto.

Fig. XI is a detail perspective view showing a modified construction of the stringer 75 and attaching lug.

Fig. XII is a detail elevation view from the outside, showing the door structure as incorporated into my improved side wall.

Fig. XIII is an inside elevation view of 80 such door structure, showing details of construction.

Fig. XIV is an enlarged detail section view showing the details of construction and manner of support of the section above 85 the door, the same being taken on line 14—14 of Figs. XII and XIII.

Fig. XV is an enlarged detail horizontal sectional view on line 15—15 of Figs. XII and XIII, showing the details of hinging 90 and supporting the door and adaptation of the same to use in this relation.

Fig. XVI is a detail view showing the manner of connecting the wall sections to the stringers in the main wall. 95

Fig. XVII is an enlarged detail sectional view taken on a line corresponding to line 17—17 of Fig. XII.

Considering the numbered parts of the drawings, interchangeable sheet metal sections 1 are supported by and connected to the stringers 2—2 which are carried by the upright posts 3—3. The stringers 2 are secured to the posts 3 by bolts 4 therethrough. Suitable clip plates 5 are interposed between 100 the parts, having rearwardly-projecting lugs 6—6 which engage the post and for- 105

wardly-projecting lugs 7-7 which engage each side of the stringer. A corner clip iron 8 is made use of at the corners, the same being suitably bent and being provided with rearwardly-projecting lugs 9-9 to engage the post, and outwardly-projecting lugs 10-10 to engage the stringers at each side of the corner. These clip plates are distinctly illustrated in Figs. V and VII.

10 An angle iron metal frame 11 is provided for each panel or section 1. This is folded into a continuous frame and an electrically welded joint 12 joins the ends. One 15 limb of the L-shaped angle bar lies in the plane of the face of the section and the other limb projects rearwardly therefrom. The main part of the section consists of the supported sheet metal plate 13, the plate 13 being folded back upon the flange of the frame at 14, as indicated in Fig. VIII.

20 A sheet metal tongue piece 15 is suitably conformed to this flange and is secured in place by the spot electric welds 16-16, as clearly appears in Figs. VIII and IX. The tongues are adapted to mesh with each other as indicated in Fig. IX. The tongues might be riveted in place, and they are preferably formed with an angular bend and 25 conformed to the angular cross section of the frame 11.

25 The sheet metal sections 1 are secured to the stringers 2 by the L-shaped slot 17 cut in the angular projecting portion of the frame 11, see particularly Fig. VI. Lugs 30 18 are secured to the under side of the stringers 2 at intervals along the front edge thereof by a suitable welded joint 18', electric welding being usually adopted for this purpose.

35 It will be seen from this description that a section 1 can be very readily inserted in place. I draw the sections toward each other and retain them in position by means 40 of bolts 19, which are inserted through perforations in the rib of the frame 11, which bolts extend through angular brackets 21, which are adjustably secured to the horizontal limb of the stringers 2. The angular 45 brackets adapt themselves to the direction of pull of the bolts 19. These bolts are disposed in somewhat angular relation at the corners, see Fig. II, and in substantially straight lines in the wall structures, see particularly Fig. XVI.

50 By this means the stringer rails are not encumbered by projecting parts and very readily nest together for shipment. At the same time, the clamping bolts for drawing 55 the sections together completely and effectively adapt themselves to this use and are very readily drawn up by applying a wrench to the nuts thereon.

60 The corner irons 23 for the walls are folded to the proper angle for the corner and

the vertical edges thereof are folded upon themselves at 24 to form a bead, and the projecting metal is folded backwardly upon itself at 25 to form a suitable engaging tongue to fit into the tongue and groove 70 structure in the edges of the panels 1 as clearly appears in Fig. II. These corners are secured in place by diagonal bolts 26, which secure clip pieces 27 against the inwardly-projecting flanges of the corner 75 irons. These bolts are disposed through triangular corner blocks 28 arranged in the corner posts so that the parts can be very securely drawn together by turning the nuts on said bolts inside the wall. As many of 80 these clips or bolts are made use of as circumstances and the height of the wall may require.

85 The lug for retaining the sheet metal wall section 1 in place may be formed as indicated in Fig. XI by striking down a lug 29 from the horizontal limb of the stringer 2. This somewhat weakens the structure and calls for extra manipulation and is not so satisfactory as the structure referred to 90 in Fig. X.

95 When it is desired to introduce a door into my wall structure, I provide a door 30 which has frame 31 of L-shaped angle metal similar to the outer frame of the wall section 1. The door is formed of sheet metal and secured to the said frame 31 by folding the edges thereof, as clearly appears in Figs. 100 XIV, XV and XVII. The door is supported by a cross brace 32 and diagonal braces 33-33 and is carried on hinges 35, which are riveted or bolted thereto as by bolts or rivets 36. The opposite members of the hinges are secured to the sheet metal panel 13 of the adjacent sheet metal section 1 by 105 rivets 37 or other suitable means.

110 A panel or wall section 38 is inserted in the space left above the door and is supported on horizontal bars 40 at that point. These bars 40 are secured to the adjacent 115 section 1 in any suitable way. The wall section 38 is made precisely like the section 1, except of small dimensions, being provided with a frame 39 of angle bar corresponding to the frame 11 and is secured to the horizontal bars 40 by precisely the same means as that adopted for securing the sections 1 on the stringers 2. The edges of the door 30 fit against the projecting tongues 15 of the adjacent sections, which makes a 120 tight joint for the door. A tongue 41 is provided on the lower edge of the section 38 above the door for this purpose at that point.

125 From this description it will be understood that my improved structure is very simple to manufacture. The parts are interchangeable, are very readily adjusted to place, and when the wall is put into place, a substantial and water-tight structure, very 130

effective for use in portable houses is provided. The structure is also of very great advantage for sign board uses, as the sections can be assembled temporarily together 5 within a suitable inclosure and the painting, decorating and lettering of the signs may be done indoors at any time and as soon as properly prepared they can be carried out and put on the stringers by unskilled labor 10 at a minimum of expense and very rapidly, making it possible to accomplish the renewal or exchange of signs with great expedition. On the other hand, where the structure is made use of for a house, the entire 15 house can be disassembled and there is no need to study the arrangement and to letter or mark the parts because the various sections are absolutely interchangeable. The door section can be inserted at any point 20 desired and the side walls can be transported in a very compact form and as the edges of the sections are supported by angle bar frame pieces, they will be found very durable and the structure is not likely to get 25 out of order during transportation.

In many particulars, my invention is an improvement on the structure invented and patented by F. W. Ruby, No. 957,259, dated May 10, 1910.

Having thus described my invention, what I claim as new and desire to secure by Letters Patent is:

1. The combination of interchangeable sheet metal sections; sheet metal tongues secured to the sides of said sections projecting beyond the edge thereof to form tongue and groove joints between the adjacent sec- 30 tions; corner posts; a corner finishing section of sheet metal folded upon itself to form side grooves to receive the edges of the interchangeable side sections, and with its edges folded to form tongues engaging the grooves of the interchangeable side sections; clip members disposed diagonally across the corners engaging said corner finishing section at said grooves and clamping the same against the said side sections; and diagonal screw bolts through the said clip members and corner post disposed with nuts inside for clamping the same in position, all 35 coacting as described and for the purpose specified.

2. The combination of interchangeable sheet metal sections; corner posts; a corner finishing section of sheet metal folded upon itself to form side grooves to receive the edges of the interchangeable side sections; clip members disposed diagonally across the corners to engage said corner finishing section at said grooves and clamp the same 40 against the said side sections; and a diagonal screw bolt through the said clip members and corner post disposed with nuts inside for clamping the same in position, all 45 coacting as described and for the purpose specified.

In witness whereof, I have hereunto set my hand and seal in the presence of two witnesses.

HOWARD M. LEONARD. [L. S.]
